STAPLE FOR STAPLING MACHINES

William Drypolcher, Valley Stream, N. Y., assignor to Lou Obstfeld, Brooklyn, and Abraham Obstfeld, New York, N. Y.

Application December 23, 1950, Serial No. 202,535

2 Claims. (Cl. 85—49)

1

This invention relates to the art of stapling, and more particularly to an improved staple for use in an improved stapling machine.

The primary object of my invention is to generally improve the art of stapling, and more especially stapling machines and thin wire staples such as are usually cemented together side by side to form a channel-shaped stick or bar of staples.

A more specific object is to avoid jamming of staples in the staple magazine. Such a jam prevents further feed of staples by the staple feed spring, thus rendering the machine inoperative.

In a prior Patent No. 2,421,429, issued to Lou Obstfeld on June 3, 1947, there is disclosed a stapling machine and a staple having the usual straight crown with two depending legs, but with one of the legs sloping outwardly relative to the perpendicular. This staple was intended to eliminate staple feed jams resulting from rotation of a free staple about its crown until the legs point toward the legs of next adjacent staples alongside of which they then become wedged. The sloping leg or so-called "sprung" leg staple, in cooperation with a staple magazine having a matingly sloped passage, effectively prevents staple jams of this character.

Nevertheless on some occasions a different type of staple feed jam may occur, and I have found that this arises from a situation in which there happens to be a loose staple at the rear end of the staple stick immediately adjacent the staple pusher. The pusher tends to wedge under the loose staple, resulting in a jam which interferes with staple feed.

One object of the present invention is to overcome staple jams of this character without, however, requiring a reduction in the tolerance or clearance between the staples and the staple magazine, for the use of a small tolerance or close fit greatly increases the manufacturing expense, particularly so when making the machines out of heavy gauge sheet metal, for there is always a certain amount of spring or opening up of the material after it leaves the forming dies. There are also irregularities in the thickness of the metal used.

To accomplish the foregoing objects, and other more detailed objects which will hereinafter appear, my invention consists in the staple and machine elements, and their relation one to another, as are hereinafter more particularly described in the specification and sought to be defined in the claims. The specification is accompanied by drawings, in which:

2

Fig. 1 is a partially sectioned side elevation of a stapling machine embodying features of my invention;

Fig. 2 is a front elevation of a staple embodying features of my invention;

Fig. 3 is a transverse section taken approximately in the plane of the line 3—3 of Fig. 1;

Fig. 4 is a fragmentary section longitudinal of the magazine taken approximately in the plane of the line 4—4 of Fig. 3;

Fig. 5 is a section similar to Fig. 3, but explanatory of the operation of the invention;

Fig. 6 is a section similar to Fig. 4 and is explanatory of a feature of the invention;

Fig. 7 is a section taken approximately in the plane of the line 7—7 of Fig. 6;

Fig. 8 is a perspective view showing parts of the machine including a wear plate used at the forward end;

Fig. 9 is a partially sectioned side elevation like a part of Fig. 1, but drawn to enlarged scale;

Fig. 10 is a similar view showing the relation of the parts when only one staple remains in the machine;

Figs. 11 and 12 show an earlier staple before and after straightening of the slope leg;

Figs. 13 and 14 show the present staple before and after straightening of the slope leg;

Fig. 15 shows the staple in relation to the staple drive channel; and

Fig. 16 is a view generally similar to Fig. 15 but showing a modification.

Referring to the drawing, and more particularly to Fig. 1, I there show schematically a desk stapling machine of generalized type, said machine comprising a base 12 carrying a clenching anvil 14. A stapling arm 16 is pivotally mounted on base 12 and comprises a staple magazine 18 through which staples are fed forwardly by means of a feed spring (not shown) toward a staple driving blade 20, the latter being operated by a suitable plunger 22.

Referring now to Fig. 2 of the drawing, the staple of my invention has a crown 24 which is concave or downwardly offset or depressed at the middle. There are two legs 26 and 28 depending from the crown 24. In preferred form the leg 26 is perpendicular to the crown, or rather to a horizontal line representing the average or mean position of the crown. The other leg 28 slopes at an angle to the perpendicular. The wire is preferably a slender, uniform, readily deformable wire of the type commonly employed for desk stapling machines, a large number of these staples being cemented together in

face-to-face relation to form a staple bar or stick. The slope of the leg 28 may range from five to thirty degrees from the perpendicular, and preferably has a slope in the range of from ten to fifteen degrees.

The advantage of the sloping or sprung leg is fully explained in the previously mentioned Patent 2,421,429 to Obstfeld, but briefly, and with reference to Figs. 5, 6 and 7, it may be explained that in the event of turning of a staple about its crown, as indicated at 30 in Fig. 6, the amount it can turn is strictly limited, for the reason that the width of the staple at the lower end of the sloping leg 28 is wider than the upper part of the magazine. In other words, as the tip 32 of the staple rises it reaches the outer wall 34 of the magazine, as is best shown in Fig. 7, which prevents further turning of the staple. When it can turn only a limited amount, say less than forty-five degrees, the pressure of the staple pusher moves the staple back into desired upright position.

Referring now to Figs. 3 and 4, the staple magazine comprises a staple core 36 and an outer wall 38 with a staple guide passage therebetween. The top portion 40 of the staple core is shaped to receive the concave crown 24 of the staples. This may be done by bending the material of the core, or by cutting away the top wall of the core, or part of each as here shown. The outer wall 38 is left straight.

The staple pusher 42 is made of sheet metal bent to fit around the staple core 36. The top forward edge 44 of the pusher is not depressed or concave like the staple crown, but instead is straight. It normally bears against only the end portions of the crown, as shown in Figs. 3 and 4.

Because of the preferably generous clearance in the staple magazine a loose staple may sometimes rise somewhat from the staple core, as is indicated by the lifted crown 24 in Fig. 5 of the drawing. With a straight crown as heretofore employed this situation has sometimes led to staple jams because the rather strongly pressed pusher 42 will tend to wedge beneath the staple. It will be evident from inspection of Fig. 5, however, that this cannot occur with the depressed crown 24, for even when the ends of the crown rise from the staple core 36 the center portion of the crown still is low enough to come in front of the straight, forward edge of the pusher. Thus by using a downwardly offset crown, in addition to the sloping leg, staple feed jams are avoided whether caused by a loose staple in the middle of the staple stick, or at one end of the staple stick.

The pusher is preferably provided with means to prevent rising, and in the present case this takes the form of a pair of flanges 46 bent inwardly at the bottom of the pusher beneath the staple core 36. These flanges hold the pusher on the core and, of course, a similar result may be obtained in other ways, for example by providing a yieldable projection or tongue at the top of the pusher to ride resiliently against the bottom face of the top outer wall 38 of the magazine. The selection of the particular means to inhibit rising of the pusher depends to a large extent on the surrounding structure of the stapling machine, for if the staple core is secured directly to an outer wall at the bottom of the stapling arm it would not be feasible to use inward flanges at the bottom.

There are three kinds of tolerance involved which often work to counteract one another but

which in some cases may all add in one direction. One has to do with the thickness of the material itself. Another results from the forming or pressing operations in the dies. The third results during assembly. The assembly tolerance sometimes may amount to more than the material tolerance plus the operations tolerance combined.

The staple core 36 is formed out of sheet metal which is much thinner than the outside wall 38 of the staple magazine. The staple pusher 42 may also be made of relatively thin sheet metal. With this thin material the material tolerance and the pressing operation tolerance are much smaller than is the case with thick metal. It is therefore entirely feasible to make the pusher 42 fit the core 36 far more accurately than the fit of the staple in the magazine, for a similar close tolerance cannot readily be provided between the core and the outside wall 38, the latter being made of heavy sheet metal. Also the assembly tolerance between relatively long major parts, such as the core and the outside wall 38, is greater than the assembly tolerance in a sub-assembly involving only the staple pusher and the core.

Referring now to Figs. 8, 9 and 10 of the drawing, the staple core 36 receives staples 50 which are urged forward by staple pusher 42 previously referred to, under the influence of a compression spring behind the pusher, but not shown. The outer wall or housing of the staple arm is indicated at 38. At its forward end the stapling arm is provided with a wear plate 54, and it will be understood that when the parts of the machine are assembled the forward end of core 36 substantially abuts the wear plate 54. The wear plate has a slot with a straight leg portion 56, a sloping leg portion 58, and a concave top portion 60, these being shaped and dimensioned to freely pass the staples 50. However, because of the concave slot 60 and the straight, forward top edge 44 of the pusher 42, the pusher cannot pass the front wear plate 54, and instead is arrested against further movement. This is illustrated by the change from Fig. 9 to Fig. 10. In Fig. 9 the pusher 42 bears against staples 50 and urges them into the staple driving slot 62 where the endmost staple comes beneath staple driver 20. When the staples have been used the last staple, indicated at 64 in Fig. 10, remains in the wear plate 54, the pusher being arrested in the position 42 with its front edge behind the wear plate.

The wear plate is preferably made of material having approximately the same gauge or thickness as the width of a staple, so that one staple remains unified at the end of the clip. Because of the concave shape of the slot in the wear plate, contrasted with the straight shape of the forward top edge of the pusher, the wear plate prevents the pusher from moving further, and thus no additional means is needed to guard against the possibility of the pusher moving so far forward as to enter the drive channel where it could be damaged by the staple driving blade.

If desired the front wear plate may be arranged to form a yieldable staple drive channel, generally as disclosed in my Patent 2,289,307 issued July 7, 1942, and entitled "Stapling Machine." For that purpose the wear plate 54 is formed integrally with a top member 66 which is pressed downward by a compression spring 68 (Fig. 9). This urges plate 54 forward about corner 55, but there is clearance at 51. The plate may be anchored by lugs 59 struck downwardly from top

66 and received in slots 61. The spring 68 is preferably the restoring spring for the staple driving plunger, and thus serves a dual purpose. It should be understood that while I have described the pusher as including means to prevent it from rising the use of such means is not essential. In theory it may be supposed that a staple jam might occur from rising of the pusher, but over a long period of time in which staple jams have been examined it invariably has been found that the jam is caused by the pusher sliding beneath the staple, and not vice versa. I am not certain of the reason for this, but may advance a possible explanation to which, however, I do not mean to be limited, because the invention may be based on the fact that it is found from empirical study that it is the staple rather than the pusher which rises. The possible explanation is that when the staple stick has become short the downward pressure of the staple driving blade on the 20 endmost staple tends to rock or turn the stick, thus raising the rear end of the stick, and so encouraging a jam in which the pusher moves beneath the staple, rather than vice versa. If the rearmost staple is partially loose the legs 25 spread readily, thus encouraging the jam, and even when the rearmost staple is not initially loose it tends to be freed from the stick by the jamming action of the pusher.

For the foregoing reasons I consider the use of 30 special means to prevent rising of the pusher to be a refinement which is not at all essential to practice of the invention. The benefits of the present improvement are great even when the pusher is devoid of special means to prevent 35 it from rising.

The combination of the concave crown and the sloping leg has particular advantages. One of these may be described with reference to Figs. 5, 6 and 7 of the drawing. When a loose staple adjacent the pusher rises, as shown in Fig. 5 it is still pressed forward by the pusher. However, with this pressure exerted against the central and lowermost portion of the crown there may be a tendency for the pressure of the pusher to turn the 45 staple about its upper corners, somewhat as indicated in Fig. 6. Without the sprung leg or slope leg this might itself tend to cause a feed jam, but inasmuch as the sprung leg is specifically designed to prevent or limit turning of a staple in this 50 fashion, no difficulty arises.

Another advantage in combining the concave crown with the slope leg may be illustrated with reference to Figs. 11 through 15 of the drawing. Fig. 11 shows a slope leg staple of the prior type having a straight crown. In driving the staple the slope leg 70 is cammed inward to perpendicular position by means indicated in Fig. 15, which shows the staple drive channel 72 enlarged at 40 to receive the staple 76, and having a cam surface at 78 to bend the sloping leg inward as the staple is driven by the staple driver 20. Referring now to Fig. 12, it will be seen that when the sloping leg 70 is bent in to the position 70' there is a tendency for the crown to convex slightly, which 55 somewhat reduces the holding effect of the staple after it has been clenched. Fig. 13 shows the present improved staple with its concave crown 24. In Fig. 14 it will be seen that the bending inward of the slope leg to the perpendicular position 28' may tend to somewhat straighten the concave crown as indicated at 24', but it will not convex the crown.

Moreover, the fact that the outward sprung leg is cammed straight results in a snug fit of the 75

staple legs in the drive channel to get maximum penetrating power. The fact that the crown of the staple remains slightly concave means that the straight edge of the driving blade is able to transmit the full driving power directly to the upper ends of the leg portions of the staple, and thereby maximum ease of driving is accomplished, without excessive wedging action. Therefore the new staple provides improvement not only in the feed performance of the machine but also in the driving qualities and ease of the machine.

Fig. 16 illustrates a staple drive channel generally like that shown in Fig. 15, but which omits the camming surface 78. This permits the staple to be driven with its leg in spread condition. I have found that the present staple can be successfully driven into solid material despite the spread leg, and it is possible that the direct pressure of the driving blade on the upper end of the leg is a contributing factor. Moreover, the uncammed spread leg is of advantage when seeking temporary clenching, as discussed more fully in the prior patent 2,421,429 heretofore mentioned.

It is believed that the formation of my improved staple, and the operation of the corresponding stapling machine, as well as the advantages thereof, will be apparent from the foregoing detailed description. It will also be apparent that while I have shown and described my invention in a preferred form, changes may be made without departing from the scope of the invention as sought to be defined in the following claims.

I claim:

1. A staple for use in a magazine type stapling machine having a sloping staple guide passage to receive a matingly sloping staple leg, said staple as manufactured and before being driven being formed of a uniform wire, and having a crown with two straight legs depending therefrom, said crown being slightly downwardly convex, one of said legs being perpendicular to the mean crown, and the other leg sloping outwardly relative to the perpendicular to the mean crown, said legs having substantially the same length, and said legs and crown all lying in a common plane.

2. A staple for use in a magazine type stapling machine having a sloping staple guide passage to receive a matingly sloping staple leg, said staple as manufactured and before being driven being formed of a slender, uniform, readily deformable wire, and having a crown with two straight legs depending therefrom, said crown being slightly downwardly convex, one of said legs being perpendicular to the mean crown, and the other leg sloping outwardly at an angle of from five to thirty degrees from the perpendicular to the mean crown, said legs having substantially the same length, and said legs and crown all lying in a common plane.
